UNITED STATES PATENT OFFICE.

SELDEN G. NORTH, OF PHILADELPHIA, PENNSYLVANIA, ASSIGNOR TO THE TRANSIT APPARATUS COMPANY, (LIMITED,) OF SAME PLACE.

STORE-SERVICE APPARATUS.

SPECIFICATION forming part of Letters Patent No. 325,436, dated September 1, 1885.

Application filed April 25, 1885. (No model.)

To all whom it may concern:

Be it known that I, SELDEN G. NORTH, a citizen of the United States, residing in the city and county of Philadelphia, in the State of Pennsylvania, have invented a new and useful Improvement in Store-Service Apparatus, of which the following is a specification.

My invention relates in general to that class of store service apparatus in which the traveling carrier is a basket or other goods receiver suspended from the depending arm or hanger of a one or two wheeled truck, the wheel or wheels of which travel upon an elevated inclined track composed of a single rail.

My invention relates specifically to the switch or movable rails of tracks of the above class, and its object is the construction of a switch-rail which, in the ordinary set of the parts, is closed or in alignment with the adjoining sections of the main track, but which is adapted to be by given carriers caused to automatically operate and to be thrown into conjunction with a branch track when it is desired to switch said carriers to said branch track, the carriers employed being provided, as to their depending arms or hangers, with laterally-extending trips, lugs, or projections, which are differently disposed upon the hangers of different carriers, so as to vary in height thereon, and which according to their vertical set are adapted in the travel of the carriers to encounter trigger devices connected with or adapted to operate upon mechanism for permitting said extremity to gravitate in the direction of the desired movement of the switch-rail.

Apparatus conveniently embodying a good form of my invention is represented in the accompanying drawings and described in this specification, the particular subject-matter claimed as novel being hereinafter definitely specified.

In the drawings, Figure 1 is a front perspective view of a preferred form of my device, the parts being represented in the positions which they occupy when the switch-rail is in alignment with the adjoining sections of the main track, the continuation of the main track, however, being, for clearer illustration, removed. Fig. 2 is a front elevational view of

the parts depicted in Fig. 1, representing, however, an advancing carrier in the act of tripping the opening-trigger, so as to cause the lifting of the free extremity of the switch-rail to place said rail in position to gravitate into alignment with the branch track, and thereby to transfer said carrier to the branch track. Fig. 3 is an elevational view of the parts depicted in Fig. 2, representing, however, the carrier, which has been transferred by the opening of the switch to the branch track, in the act of tripping the closing-trigger so as to occasion the lifting of the free extremity of the switch-rail to place said rail in position to gravitate into alignment with the continuation of the main track, and thereby to close the switch. In both Figs. 2 and 3 the continuation of the main track is, for clearer illustration, removed. Fig. 4 is a top plan view of the entire device, the switch being open and the switch-rail in alignment with the branch track. Fig. 5 is a similar view of the same parts, the switch being closed and the switch-rail in alignment with the continuation of the main track. Fig. 6 is a rear elevation of the apparatus represented in Fig. 5. Fig. 7 is a perspective detail of the opening-trigger removed from its housing. Figs. 8 and 9 are transverse sectional elevational details in the plane of the dotted line xx of Figs. 4 and 5, Fig. 8 representing the position which the parts bisected occupy in Fig. 4, and Fig. 9 representing the positions which said parts occupy in Fig. 5. Sight is taken in the direction of the arrows in said Figs. 4 and 5. Fig. 10 is a vertical longitudinal sectional elevation through the compound pivot of the switch-rail on the line yy of Fig. 11. Fig. 11 is a top plan view of the same. Fig. 12 is a view in perspective of the pivot removed from its framing-plate and the switch-rail. Fig. 13 is a transverse elevation of the swinging roller-plane and the roller which is applied to the switch-rail, the view being intended to illustrate two positions of the parts. Fig. 14 is a fragmentary perspective detail of a convenient construction for maintaining the free extremity of the switch-rail in close relationship with the continuation of the main track.

Similar letters of reference indicate corresponding parts.

In the drawings that portion of the main track which is in permanent conjunction with the hinged or pivoted extremity of the switch-rail is designated A, while that continuation

5 of the main track which is adapted, when the switch-rail is in its normal position, as shown in Fig. 5, to be in conjunction with the free extremity of said switch-rail, is designated A^x.

B is that portion or beginning extremity 10 of a branch track which is adapted, when the free extremity of the switch-rail is allowed to gravitate from its normal set, to be in conjunction with said extremity, and which, when in such conjunction, is connected with the 15 main track A by said switch-rail, as shown in Fig. 4.

a is a preferably horizontally-disposed framing-plate or housing with which the main track A and branch track B are connected, 20 and which is connected by a bridge or forked suspender, a^x, with a supplemental framing-plate, a², to which latter is connected the continuation of the main track A^x, the said main track, continuation thereof, and branch track 25 being in such manner connected in permanent relationship, and adapted conveniently by means of the bridge or forked suspender to be suspended from the ceiling of the apartment in which the apparatus is set up. When the 30 switch-rail is in conjunction with the branch track, a passing carrier runs under the bridge.

C is the switch-rail, which is connected by means of a compound pivot, ball-joint, or the like, with the framing-plate a in such manner that the free end of said switch-rail is capable of having imparted to it both an up and down movement in a vertical or practically vertical plane, and also of itself taking on an in and out movement with respect, respectively, to the 35 continuation of the main track A^x and the branch track B in planes slightly inclined from the horizontal. As a convenient means of forming the compound pivot, I provide the inner or pivoted extremity of the said switch-rail with a laterally-extending heel or hub, c, Figs. 10 and 11, provided with a slot, c', running parallel with the rail itself, and mount the said hub upon a stud, c², swiveled in the framing-plate a, and provided with a head, c³, 40 which is of breadth sufficient to fill the slot c' in the heel of the switch-rail, and I then apply a horizontal pivot-pin, c⁴, which passes through the heel or hub of the rail, and also through the head of the swiveled stud, as a 45 reference to Figs. 10, 11, and 12 will make clear.

By the above means, as will be readily understood, the free extremity of the switch-rail is capable of a vertical movement up and down 50 upon the horizontal pivot-pin c⁴ as an axis, while it is also capable of an in and out movement with respect to the swiveled stud c² as an axis, without regard to the vertical position of the free extremity of said rail.

55 The framing-plate a, as a reference to Figs. 1, 4, and 5 will indicate, is so shaped that ample room is provided for the lateral gravi-

tative movement of the switch-rail to place its free end in alignment either with the continuation A^x of the main track or with the branch 70 track B.

The inner side of the said switch-rail, near its free extremity, is provided with a friction-roller, d, slide, or other traveling bearing, which is conveniently mounted, preferably 75 both for free rotation and longitudinal or end for end travel, upon a horizontal axle, d', contained in a housing, D, applied to said switch-rail. The outer or free extremity of the switch-rail is also conveniently provided with an inclined face, e⁵, which is formed by beveling 80 off the substance of the outer extremity of said rail in such manner as to leave an overhanging shoulder, e⁶. That extremity of the continuation of the main track A^x which is 85 adapted to be aligned with the free extremity of the switch-rail when the switch is closed, is also provided with an oppositely-inclined face, e⁷, and with a seat, e⁸, above said face, which latter is adapted to receive the overhanging shoulder e⁶ of the switch-rail, as shown 90 in Fig. 14, the object of the construction being simply to afford certain engagement and stoppage for the free extremity of the switch-rail when the latter gravitates out to alignment with the continuation of the main track, in which latter position the inclined faces e⁵ and e⁷ register and the overhanging shoulder e⁶ rests within the seat e⁸. When the switch-rail gravitates into alignment with the branch 95 track, it encounters and is stopped by a shoulder, e⁹, or other stop in propinquity to said branch track.

E is a swinging trigger, which I term the "opening-trigger," pivoted to the framing-plate a in propinquity to and in advance of the pivoted end of the switch-rail. This trigger is represented in perspective in Fig. 7, is applied to the main track, and is conveniently formed as a swinging stirrup provided with a 105 depending trigger-lug, e, which is adapted to be encountered by the hanger-trip on given carriers, and with a horizontal forwardly-extended trigger-arm, e^x. The trigger is represented in Figs. 1, 2, 4, 5, and 6 as hung upon 110 a horizontal pivot, e², and its normal set is such that the trigger-arm e^x occupies a horizontal position, while the trigger itself and its depending lug e are vertical. The application of the trigger is also preferably such that it 115 can only be swung in one direction, or in that represented by the arrows in Figs. 1 and 6 and by the dotted lines in Fig. 2.

F is what I for convenience term a "roller-plane," the same being a movable plate, plane, 125 carrying surface, or track, so to speak, upon which rests and is adapted to gravitate, ride, or run the roller attached to the free extremity of the switch-rail. This swinging plane is adapted to be inclined either toward or away 130 from the switch-rail, and is conveniently suspended upon arms f, conveniently pivoted at their upper extremities upon the plane-shaft G, which is shown secured in standards g,

erected from the frame-plate at the sides of a recess, a^6 , formed in the plate, in which recess the roller-plane is adapted to move or swing. The space between the arms f^f is sufficient 5 for the entrance of the roller-housing on the switch-rail, as shown in Figs. 4, 8, and 9. The arms f^f of the roller-plate F are provided with rearwardly-extending cranks f^*f^{**} .

H is a connecting-lever, being a lever of the 10 first order pivoted at h above the frame-plate a , and herein termed the "opening-lever." The front extremity of this lever is conveniently connected with that crank f^* of the roller-plane which is adjacent to it, conveniently 15 by being passed somewhat loosely through a hole in the free extremity of said crank, while the rear extremity of said connecting-lever is adapted to overhang and rest upon the trigger-arm e^* of the opening-trigger E .

I is what I term the "closing-trigger," it being a swinging trigger pivoted to that portion of the framing-plate a to which the branch track B is connected. The said trigger is applied 20 to said branch track, is provided with a depending trigger-lug, i , which in the normal set of the trigger is vertical, and is also provided with a forwardly-extending trigger-nose, i^* . The set of the closing-trigger with 25 respect to the horizontal pivot i^2 upon which it is suspended, is preferably such that the trigger is only capable of a swinging movement in the direction of the arrow in Fig. 6, or into the position represented in Fig. 3.

J is a connecting-lever, being a lever of the bell-crank order, herein termed the "closing-lever," which is adapted to have movement about a horizontal pivot, j , conveniently mounted upon the framing-plate a . The lower 30 arm of this closing-lever is, as shown in Figs. 3 and 6, provided with a curved surface, j^* , against which the trigger-nose i^* of the closing-trigger operates, while the upper arm of said lever is connected with that crank f^{***} of the roller-plane which is adjacent to it, conveniently 35 by being passed somewhat loosely through a hole formed near the extremity of said crank.

K is the traveling carrier, and k the lug on 40 the hanger thereof.

Such being a description of a good construction of an apparatus embodying my invention, its operation is as follows: In the normal set of the parts the switch-rail is in alignment 45 with the continuation of the main track, as shown in Figs. 1 and 5, and in this position the movable roller-plane is in the position represented in Figs. 1, 9, and 13. It should here be remarked that the branch track B may, in 50 fact, be a continuation of the main track, and the track designated A^* be the branch track, it being of course immaterial to the invention as to where the said tracks A^* and B lead or how they are designated. When a given advancing carrier, traveling by gravity on the inclined main track, encounters by its hanger-lug the depending trigger-lug of the opening-

trigger it will occasion a forward deflection of the said opening-trigger, as represented in dotted lines in Fig. 2, with the result that the trigger-arm e^* of said opening-trigger will be thrown up and the opening-trigger deflected from the position which it is represented as occupying in Figs. 1 and 6, to that which it is represented as occupying in Fig. 2, and with 75 the further result that the said deflection of said opening-lever will, through its connection with the crank f^* , occasion such a movement swinging or tilting of the roller-plane as will effect the vertical lift of the outer or free extremity of the pivoted switch-rail, as shown in Fig. 2.

So soon, however, as said roller-plane has been tilted and the switch-rail lifted, as above set forth, the plane, as will be obvious first by 80 a reference to the dotted lines of Fig. 13, and then to Fig. 8, will present such an inclined surface that the roller connected with the free extremity of the pivoted switch-rail will gravitate upon the carrying-surface of said plane from the position which the said roller is represented in dotted lines as occupying in said Fig. 13 to that which it is represented as occupying in said Fig. 8, with the result that the free extremity of the switch-rail will, by 85 such gravitational movement alone, be caused to become aligned with the continuation of the main track. This entire action, first, of the positive lifting of the free end of the switch-rail, and, second, of the uncontrolled gravitational 90 movement of said free end of said switch-rail by its roller over the inclined plane, will take place before the carrier has reached the hinged extremity of and has traveled upon the switch-rail. When the said carrier has tripped the 95 opening-trigger, and thereby occasioned the gravitational movement of the switch-rail to a position in alignment with the branch track, as shown in Fig. 4, it will run upon and over said switch-rail until it reaches and travels 100 upon the said branch track. As, then, said carrier travels along said branch track its hanger-lug will encounter the depending trigger-lug i of the closing-trigger I , as represented in Fig. 3, and, through the deflection of said 105 closing-trigger operating by its nose against the curved surface j^* of said closing-lever, will occasion such a deflection of said lever as through its connection with the crank f^{***} of the movable roller-plane will occasion the deflection of said plane in such manner as, first, to cause it again to lift the free extremity of the switch-rail, as shown in Fig. 3; and, second, to place its inclined surface in such position that the switch-rail will instantly upon 110 the completion of its lift, by means of its roller, gravitate over said inclined plane outward until its free end is once more in alignment with the continuation of the main track, so that the next succeeding carrier will find the 115 switch-rail in alignment with the main track, and will in consequence travel across said switch-rail onto said main track unless its hanger-lug is so disposed as to encounter the open-

ing-trigger, in which event the entire operation above described will be repeated and the carrier transferred to the branch track.

It will from the foregoing description be readily understood that the whole operation of the opening-trigger and opening-lever upon the movable roller-plane is simply such as to impart a given deflection or inclination to said plane, so that said deflection will permit the gravitational movement of the switch-rail into alignment with the branch track; that, moreover, on the other hand, the operation of the closing-trigger and closing-lever is essentially similar, the carrier encountering the closing-trigger occasioning through the deflection of the closing-lever such a reverse tilt or inclination in the roller-plane as will place the plane in such position that the roller of the switch-rail must gravitate over it until the switch-rail is again aligned with the main track. The opening-trigger and the closing-trigger being, respectively, applied to an extremity of the main track and to an extremity of the branch track, respectively, adjacent to the switch-rail, it is obvious that the entire operation of the movement of the switch-rail will be accomplished when the carrier is either upon the main track or upon the branch track, and will not take place while the carrier is on the switch-rail. Both triggers and both levers are applied, respectively, in conjunction with the main and branch tracks simply and wholly for the purpose of enabling the carrier automatically to operate the movable roller-plane, so as by the inclination of the plane to permit the gravitational movement of the roller connected with the free extremity of the switch-rail in one or the other directions across the surface of the then properly-inclined roller-plane. The movable roller-plane, therefore, is a device which subserves the purpose of being an adjustable inclined plane, adapted to be inclined in either direction, over the inclined surface of which the roller connected with the switch-rail may freely gravitate, so that said switch-rail may by a gravitational movement alone be placed in alignment either with a continuation of the main track or with the branch track.

It may be well to explain that I employ the word "gravitative" and the words "gravitative lateral" in this specification in a sense not perhaps technically exact, but as indicating both the character and direction of movement of the switch-rail, which, while lateral in the sense that it is from side to side, is gravitative in that it is a "down-hill" movement occasioned by the force of gravity.

It is of course essential that the closing-trigger should be applied to the branch track and be adapted to be operated upon by every carrier transferred to said branch track, as otherwise the switch-rail previously caused through the intervention of the opening-trigger to move its position from alignment with the main track to alignment with the branch track would be left in alignment with said

branch track, so that any succeeding carrier would of necessity travel across the switch-rail onto the branch track, even if it were desirable that said carrier should travel over the switch-rail onto the continuation of the main track. The depending trigger-lug of the opening trigger and the depending trigger-lug of the closing-trigger are therefore preferably of the same length, so that a lug in suitable position upon the hanger of a given carrier to operate the opening-trigger will also operate the closing-trigger. Of course those carriers the lugs of which are not in position to encounter the opening-trigger can never encounter the closing-trigger, because if the opening-trigger is not operated the switch-rail remains in its normal position of alignment with the continuation of the main track, and the carrier travels along said switch-rail onto said continuation, and the converse of this condition is, as stated, true, for if the lug on the hanger of the carrier is so placed as to encounter the opening-trigger, it must also be so placed as to encounter the closing-trigger, and therefore after a given carrier has been by the switch transferred to the branch track it will of necessity automatically operate said closing-trigger, so that said switch-rail will gravitate back to alignment with said main track.

While I have represented, and with some particularity described, a specific construction of an opening-trigger and opening-lever, and of a closing-trigger and closing-lever, I yet desire it to be understood that the opening and closing triggers may be of any suitable construction, and that the opening and closing levers are simply intermediate devices adapted to transmit the movement of the said triggers to the swinging roller-plane, and that, therefore, the triggers themselves may be arranged to operate the plane, or other intermediate connecting or motion transmitting devices than the said opening and closing levers may be substituted for the same purpose in their stead, with perhaps the same effectiveness of operation, the essential idea of this part of my invention residing in the provision of such a trigger mechanism, to be operated by given carriers, as will, when operated, occasion, either directly or through the intervention of suitable devices, a deflection of the roller-plane in one or the other direction, the operation of said roller-plane being, as already fully stated, to present such an inclination of its carrying-surface in one or the other direction as will permit the roller connected with said swinging switch-rail to gravitate over said surface in said direction. Of course, as stated, the switch-roller may be omitted, and a slide or other bearing connected with the switch-rail and adapted to slide or move on the surface of the roller-plane be substituted in its stead.

While I have also shown and described the movable roller-plane as suspended from an axis disposed above it, it is an equally simple construction to support or pivot it from below, and to dispose the opening and closing levers

or their equivalents below the framing-plate. In fact, as already stated, the form and mode of application of the said levers, as well as of the triggers and movable plane, are immaterial to the broad idea of the invention, which resides in the provision of suitable mechanism adapted to be tripped or operated by the traveling carrier, for, through the intervention of an inclined surface, bringing about the gravitational movement of the switch-rail.

It is of course possible for a skillful mechanic to make many modifications in a device such as this, which is essentially mechanical, and all the benefits of my invention flow from the provision, in connection with a track, a traveling carrier, and a movable switch-rail, of an inclined surface *per se*, which, through and by means of any suitable intermediate mechanism tripped, operated upon, or controlled by the carrier, is presented to the switch-rail as a plane over which said rail may take on a gravitational movement in the desired direction, the said gravitational lateral movement being the distinguishing characteristic of my device. The precise form or character of the intermediate mechanism is not, therefore, of the essence of the invention, and any mechanical contrivance or combination of mechanical powers adapted to be operated upon by the traveling carrier and to permit the lateral gravitational movement of the switch-rail over an inclined surface is adapted, in connection with the positive elements of a track, a movable switch-rail, an inclined surface, and a traveling carrier, to effectuate the said result, and is therefore the mechanical equivalent of the trigger, trigger-lever, and movable plane represented and described.

It is also proper for me to state that while I have represented (in Figs. 1, 2, and 3) and described my improvements as embodied in a switch over which a carrier travels from left to right, yet that it is of course competent for me to rearrange the devices so as to adapt the switch to operate with a carrier running over it from right to left, and that such a change necessitates not only the entire redispersion of the component parts, but also in some instances the application of other motion-transmitting devices than those represented and described. The principle, however, remains the same.

It is also easy, without departure from the invention, to arrange the switch-rail to move to a branch track which lies upon the opposite side of the track A^x from the side on which the track B is in the drawings represented as lying, such a change necessitating simply a local rearrangement of parts.

Having thus described my invention, I claim—

1. In a store-service apparatus, the following elements in combination: an elevated track, a traveling carrier, a switch-rail, and mechanism, substantially such as described, or its equivalent, adapted to be actuated by the carrier to permit the gravitational lateral move-

ment of said switch-rail, substantially as and for the purposes set forth.

2. In a store-service apparatus, the following 70 elements in combination: a main track, a switch-rail, and an inclined plane with respect to which the switch-rail has a gravitational lateral movement, substantially as set forth.

3. In a store-service apparatus, the following 75 elements in combination: a main track, a switch-rail provided with a roller, slide, or traveling bearing, and an inclined plane upon which said roller rests and travels, substantially as set forth. 80

4. In a store-service apparatus, the following elements in combination: a main track, a traveling carrier, a switch-rail provided with a roller, slide, or traveling bearing, an inclined plane upon which said roller rests and travels, 85 and means adapted to be set in action by the traveling carrier for permitting the gravitational movement of the switch-rail with respect to the inclined plane, substantially as set forth.

5. In a store-service apparatus, the following 90 elements in combination: an elevated track, a traveling carrier, a switch-rail, and mechanism adapted to be actuated by the carrier in its travel, for, first, lifting the switch-rail, and second, permitting the gravitational lateral 95 movement of said lifted switch-rail, substantially as set forth.

6. In a store-service apparatus, the following 100 elements in combination: an elevated track, a traveling carrier, a switch-rail adapted to move both vertically and laterally, means actuated by the carrier in its travel for raising the switch-rail, and means controlled primarily by the carrier for the gravitational lateral movement of the switch-rail, substantially 105 as set forth.

7. In a store-service apparatus, the combination of a track, a switch-rail, and a compound pivot connecting said switch-rail with said track, the arrangement being such that 110 the switch-rail is adapted both to be lifted and to gravitate laterally with respect to said pivot, substantially as set forth.

8. In a store-service apparatus, the following 115 elements in combination: an elevated track, a traveling carrier, a switch-rail, a movable plane adapted to be inclined toward or away from the switch-rail, a device connected with the switch-rail which bears and travels upon said movable plane, and mechanism 120 adapted to be actuated by the traveling carrier for imparting inclination to said plane, substantially as and for the purposes set forth.

9. In a store-service apparatus, the following 125 elements in combination: a main track, a switch-rail provided with a roller, slide, or traveling bearing, a movable plane upon which said roller rests and travels, and means adapted to be set in action by a traveling carrier for imparting inclination to said plane, 130 for the purpose, first, of lifting said switch-rail, and, second, of permitting its gravitational movement, substantially as set forth.

10. In a store-service apparatus, the follow-

ing elements in combination: a main track, a continuation thereof, a branch track, a movable switch-rail adapted to connect the main track either with its continuation or with the branch track, a traveling carrier, means applied to the main track and adapted to be actuated by the carrier for first lifting the free extremity of the switch-rail, and then permitting its gravitational movement into the branch track, and means connected with the branch track and adapted to be actuated by the carrier for first lifting the free extremity of the switch-rail and then permitting its gravitational movement out to the continuation 10 of the main track, substantially as set forth.

11. In a store-service apparatus, the following elements in combination: a main track, a traveling carrier, a switch-rail provided with a roller, slide, or traveling bearing, a movable plane, an opening-trigger, and an opening-lever, substantially as and for the purposes set forth. 15

12. In a store-service apparatus, the combination of a main track, a switch-rail, a traveling carrier, a movable plane adapted to both lift the free extremity of the switch-rail and permit of the gravitational movement of said free extremity, and mechanism in advance of the switch-rail, adapted to be actuated by a carrier, for occasioning a given movement of said plane and a consequent lift and given gravitational movement of the switch-rail before the carrier runs upon said rail, substantially as set forth.

13. In a store-service apparatus, the combination of the main track, a switch-rail, a branch track, a traveling carrier, a movable plane adapted to both lift the free extremity of the switch-rail and permit of the gravitational movement of said free extremity, and mechanism beyond the switch-rail adapted to be actuated by a carrier for occasioning a given movement of said plane and a consequent lift and given gravitational movement of the switch-rail after the carrier has run off said rail, substantially as set forth.

14. In a store-service apparatus, the combination of a main track, a switch-rail, a branch track, a traveling carrier, a movable plane adapted to both lift the free extremity of the switch-rail and permit of the gravitational movement of said free extremity, mechanism in advance of the switch-rail adapted to be actuated by a carrier for occasioning a given movement of said plane and a consequent lift and given gravitational movement of the

switch-rail before the carrier runs upon said rail, and mechanism beyond the switch-rail adapted to be actuated by a carrier for occasioning a given movement of said plane and a consequent lift and given gravitational movement of the switch-rail after the carrier has run off said rail, substantially as set forth. 65

15. In a store-service apparatus, the combination of a main track, a traveling carrier, a switch-rail provided with a roller, slide, or traveling bearing, a movable plane, an opening-trigger, and an opening-lever, substantially as and for the purposes set forth. 70

16. In a store-service apparatus, the combination of a main track, a traveling carrier, a switch-rail provided with a roller, slide, or traveling bearing, a branch track, a movable plane, a closing-trigger, and a closing-lever, substantially as and for the purposes set forth. 75

17. In a store-service apparatus, the combination of a main track, a traveling carrier, a switch-rail provided with a roller, slide, or traveling bearing, a movable plane, an opening-trigger, an opening-lever, a closing-trigger, and a closing-lever, substantially as and for the purposes set forth. 80

18. In a store-service apparatus, as a device for imparting given inclinations to a movable plane, an opening-trigger, an opening-lever, a closing-trigger, and a closing-lever, substantially as set forth. 85

19. In a store-service apparatus, the combination of a pivoted switch-rail, the free extremity of which is provided with an inclined face and a shoulder, and a continuation of the main track, the opposing extremity of which is provided with an oppositely-inclined face and a seat, as and for the purposes specified. 90

20. In a store-service apparatus, the combination of a main track, a switch-rail provided with a compound pivot and with a roller-housing equipped with a roller, and a movable plane upon which said roller treads and travels, substantially as set forth. 100

21. In a store-service apparatus, the following elements in combination: a main track, a switch-rail, a traveling carrier, an inclined plane, with respect to which the switch-rail has a gravitational lateral movement, and means adapted to be set in action by a traveling carrier for permitting the gravitational lateral movement of the switch-rail with respect to the inclined plane, substantially as set forth. 105

In testimony whereof I have hereunto signed my name this 24th day of April, A. D. 1885.

SELDEN G. NORTH.

In presence of—

J. BONSALL TAYLOR,
WM. C. STRAWBRIDGE.

Correction in Letters Patent No. 325,436.

It is hereby certified that in Letters Patent No. 325,436, granted September 1, 1885, upon the application of Selden G. North, of Philadelphia, Pennsylvania, for an improvement in "Store-Service Apparatus," an error appears in the printed specification requiring the following correction: In line 104, page 5, the word *permitting* should be inserted between "for" and "the"; and that the said Letters Patent should be read with this correction therein that the same may conform to the record of the case in the Patent Office.

Signed, countersigned, and sealed this 15th day of September, A. D. 1885.

[SEAL.]

Countersigned:

M. V. MONTGOMERY,
Commissioner of Patents.

G. A. JENKS,
Acting Secretary of the Interior.
